SKI GRIPPING CLEAT

Jean M. Mercier, Dover, N. H.

Application September 11, 1953, Serial No. 379,643

4 Claims. (Cl. 280—11.37)

This invention relates to attachments for skis, and in particular a snow gripping blade or cleat pivotally mounted on a ski and adapted to be adjusted to extend downwardly into snow at one side of the ski to facilitate hill climbing on skis.

The purpose of this invention is to provide a snow gripping cleat that prevents a ski sliding backward, particularly in hill climbing and that obviates the necessity of walking with skis in a V or sideways.

Various types of attachments have been provided for preventing skis sliding backward when walking in snow and other devices have been used in combination with skis for facilitating walking when returning to the top of an incline or the like, however, such devices interfere with normal use of the skis. With this thought in mind this invention contemplates a cleat pivotally mounted on a ski and adapted to nest in a flat position against the upper surface of the ski when not in use and adapted to be adjusted to a vertical position when it is desired to walk or climb a hill with the skis.

The object of this invention is, therefore, to provide means for mounting a snow gripping cleat on a ski whereby the cleat is turned to a nested position upon the upper surface of the ski when not in use.

Another object of the invention is to provide snow gripping cleats for skis in which the cleats are adapted to be mounted on skis now in use.

A further object of the invention is to provide adjustable snow gripping cleats for skis in which the cleats are of simple and economical construction.

With these and other objects and advantages in view the invention embodies a base plate adapted to be secured upon the upper surface of a ski, a supporting plate pivotally mounted on the base plate, a cleat carried by the supporting plate, and a brace for retaining the cleat in an operative position.

Other features and advantages of the invention will appear from the following description taken in connection with the drawings, wherein:

Figure 1 is a plan view of a ski with the attachment mounted thereon and showing a snow gripping cleat extended from one side of the ski.

Figure 2 is a side elevational view of the intermediate part of the ski showing the parts in a nested position thereon and also showing the parts on an enlarged scale.

Figure 3 is a view similar to that shown in Fig. 2 showing the cleat adjusted to a vertical position in relation to the ski whereby the cleat is adapted to grip into snow, and the like.

Figure 4 is a plan view of the intermediate portion of a ski showing the device nested upon the upper surface of the ski.

Figure 5 is a plan view similar to that shown in Fig. 4 showing the cleat extended from one side of the ski and showing the brace in a position in which it is extended from the cleat.

Figure 6 is a plan view also similar to that shown in Figs. 4 and 5 showing the cleat in the operative position

and showing a brace in the position of retaining the cleat in an operative or vertical position.

Figure 7 is a cross section taken on line 7—7 of Fig. 3 also showing the cleat in an upright or operative position.

Figure 8 is a longitudinal section taken on line 8—8 of Fig. 6 showing the brace for retaining the cleat in the upright or operative position.

Figure 9 is a cross section through the ski taken on line 9—9 of Fig. 6 showing a clip for retaining the supporting plate in the position of retaining the cleat in the upright or operative position.

Figure 10 is a cross section through the ski showing a spring clip for retaining the brace in an inoperative position.

Figure 11 is a detail showing a plan view of the supporting plate.

Figure 12 is a detail illustrating the cleat holding elements at one end of the brace with part of the brace positioned against one surface of the cleat and with a hook on another part positioned to grip the upper edge of the cleat.

Referring now to the drawings wherein like reference characters denote corresponding parts the snow gripping cleat or blade of this invention includes a mounting plate 10, a supporting plate 11 pivotally mounted on the plate 10 with a pin 12 extended through an opening 13 in the supporting plate, a cleat 14 having a beveled edge 15 for cutting into snow and the like pivotally mounted with bearings 16 and 17 on the supporting plate 11, and a brace 30 including a bar 18 that is pivotally mounted by a pin 19 on the base plate 10 and that is provided with a clip 20 on the extended end which is positioned to extend over the upper edge of the cleat, as shown in Figs. 3 and 8 to brace the plate.

The ski may also be provided with a counter-weight W to counter-balance the weight of the snow gripping cleat, the counter-weight being positioned on the opposite end of the ski.

The base plate 10 is provided with openings 21 by which it is secured with rivets or other fasteners to a ski, as indicated by the numeral 22 and, as shown in Fig. 4 a clip 23 extends from one side for supporting the plate 11 with the parts in the operative position. The clip 23 is substantially U-shaped in cross section and has a longer leg 24 which extends across a portion of the under surface of the base plate 10 and the upper surface of the ski 22. The longer leg 24 is secured to the ski 22 by screws or other fasteners 25, see Fig. 9. The base plate 10 is also provided with an angularly disposed U-shaped clip 26 in which the edge 15 of the cleat 14 is retained. The base plate 10 is also provided with an opening 27, the outer portion of which is closed by the pin 19, and a U-shaped bearing member extended around the pin 19 and secured to the bar 18 with rivets 28 provides means for pivotally mounting the brace on the base plate. The U-shaped strap or member that extends around the pin 19 is formed with a strap 29 of metal or other suitable material.

The bar 18 is also provided with a spring 30 that is secured to the bar with rivets or fasteners 31 and the clip 20 is secured to the extended end of the spring 30 with rivets or other fasteners 32 which extend through a base 33 of the clip.

A U-shaped spring clip 34 is also mounted on the ski as shown in Figs. 6 to 10 to provide means for frictionally holding the brace including the bar 18 and clip 20 in the open or inoperative position. With the parts as illustrated in Fig. 8 the upper end of the bar 18 extends through an opening 35 in the upper portion of the cleat 14.

The supporting plate 11 is formed, particularly as shown in Fig. 11 with extended tongues which are rolled to form the bearings 16 and 17 and the bearings extend through

3

openings 38 and 39, respectively in the edge of a shank 40 of the cleat 14. The shank is pivotally mounted by the bearings on the supporting plate.

The shank or tongue 40 of the cleat 14 is provided with a beveled surface 41 to provide clearance for the pin 12 and also a beveled surface 42 that registers with the side of the ski, as shown in Fig. 4 whereby the entire device is within the limits or width of the ski.

The supporting plate 11 is also provided with a beveled surface 43 that is in a plane corresponding with one side of the ski with the parts folded or nested, as shown in Fig. 4 and the opposite corner of the supporting plate 11 is provided with a recess 44, that is positioned in the upper surface and that is adapted to slide below the clip 23 to provide supporting means for the extended end of the supporting plate with the cleat 14 in the vertical or operating position.

With the parts assembled and mounted on a ski in this manner the cleat with the mounting and retaining elements is folded to a nested position upon the upper surface of a ski, as shown in Fig. 4, the parts being positioned forwardly of a toe or foot strap or brace, as indicated by the numeral 45, and with the parts folded or nested in this manner the ski is adapted to be used in the conventional manner.

A pair of skis upon which this assembly is mounted are, therefore, adapted to travel downhill or on a course in a usual manner and when it is desired to return or travel upwardly on a grade the cleats 14 are adjusted to the positions shown in Figs. 3, 6 and 8 whereby the blades of the cleats are adapted to dig into snow, or the like, either with the snow soft or hard, and the person using the skis may climb upwardly without positioning the skis in the form of a V or without treading with one ski passing over the other.

In setting the device up for use the cleat 14 is turned from the position shown in Fig. 4 to that shown in Fig. 5 and from the horizontal position shown in Fig. 5 the cleat is turned to a vertical position as shown in Fig. 6 in which position the clip 20 is placed over the upper edge with the bar 18 extended through the opening 35, as shown in Fig. 8. By the same means the brace may be removed and the cleat folded to a nested position upon the ski when use thereof is not desired.

As illustrated in Fig. 7 the cleat includes an L-shaped body having a blade extended from one end of the shank 40 and the body is adapted to swivel and fold to a nested position upon the base plate or ski.

It will be understood that modifications, within the scope of the appended claims, may be made in the design and arrangement of the parts without departing from the spirit of the invention.

What is claimed is:

1. A ski treading cleat comprising a plate having a shank with an offset blade extended from one end of the shank, a supporting plate pivotally connected to the shank of the plate forming the cleat, a base plate on which the supporting plate is pivotally mounted, and a brace pivotally mounted on the base plate and having a clip on the ex-

4

tended end adapted to be positioned over the edge of the plate forming the cleat for retaining the offset section of the plate in a downwardly extended position.

2. In a ski gripping device, the combination which comprises a base plate adapted to be mounted on the upper surface of a ski, a supporting plate pivotally mounted on the base plate and positioned to slide on the upper surface thereof, a cleat having a shank with a gripping blade extended from one end of the shank pivotally mounted on the supporting plate and adapted to be positioned, selectively, in a nested position upon the base plate and ski or in an operative position with the shank and blade positioned perpendicular to the base plate and ski, and a brace pivotally mounted on the base plate and having a clip mounted on a spring thereon for engaging the cleat to retain the cleat in the operative position.

3. A folding ski treading device comprising a base plate adapted to be permanently mounted on a ski so that the base plate is in constant contact with the ski at all times, a cleat including an L-shaped body having a shank with a blade carried by one end, a hinge for connecting the shank to the base plate, means pivotally mounting the hinge on the base plate whereby the L-shaped body of the cleat facilitates the operation of the cleat to selectively position the cleat in a flat position upon the base plate and ski, or in a position perpendicular to the base plate and ski with the blade depending from one side of the ski, means for retaining the cleat in a flat position upon the base plate and ski, and means for retaining the cleat in a vertical position with the cleat perpendicular to the ski.

4. A folding ski treading device comprising a base plate adapted to be permanently mounted on a ski so that the base plate is in constant contact with the ski at all times, a cleat including an L-shaped body having a shank with a blade carried by one end, a mounting plate, means for hinging the shank of the body to the mounting plate, means pivotally connecting the mounting plate to the base plate whereby the L-shaped body of the cleat facilitates the operation of the cleat to selectively position the cleat, in a flat position upon the base plate and ski, or in a position perpendicular to the base plate and ski with the blade depending from one side of the ski, means for retaining the cleat in a flat position upon the base plate and ski, and means for retaining the cleat in a vertical position with the cleat perpendicular to the ski.
